UNITED STATES PATENT OFFICE.

FRANCIS DE GRUCHY, OF NEWARK, NEW JERSEY.

GAS-LIGHT BURNER.

Application filed February 14, 1922. Serial No. 536,462.

To all whom it may concern:

Be it known that I, FRANCIS DE GRUCHY, a citizen of the United States, and a resident of Newark, in the county of Essex and

5 State of New Jersey, have invented new and useful Improvements in Gas-Light Burners, of which the following is a specification.

This invention relates in general to gaseous fuel burners for lighting purposes, and 10 more particularly to a gas-light burner of the flame type including a tip for spreading the flame for illuminating purposes.

The objects of the invention are to provide an illuminating burner of the character described embodying novel features of construction whereby light of high quality is obtained; to provide a construction for an illuminating burner of this character which produces substantially complete combustion 15 of the gaseous fuel and thereby a white, brilliant flame; to thus provide a burner including a pair of spaced gas outlets and improved means for directing a current of air between said outlets into the flame; to provide a burner including a body portion adapted to be connected to a gas pipe and having a pair of spaced gas outlets directed upwardly and inwardly toward each other whereby the flames from said outlets merge 20 into each other, said body portion having opposite grooves therein beneath and between said outlets whereby the heat from said flames draws air upwardly through said grooves into said flames; and to obtain other results and advantages as may be brought out by the following description.

Referring to the accompanying drawings, in which like numerals of reference indicate the same parts throughout the several views.

40 Figure 1 is an enlarged vertical longitudinal sectional view through a gas-light burner embodying my invention;

Figure 2 is a partial transverse vertical sectional view and side elevation of the burner, and

45 Figure 3 is a top plan view thereof.

In the embodiment of the invention shown on the drawings the reference character A designates the body portion of the burner which includes a tubular portion 1 internally threaded at one end thereof, as at 2, for attachment to a gas-pipe or the like, the other end of said tubular portion communicating through an opening 3 with a chamber 4, which is formed at the end thereof with an upstanding burner tip supporting

projection 5. The projection 5 is provided with a pair of spaced passages 6 communicating with the chamber 4 and converging upwardly toward each other, a burner tip 7 being mounted at the outer end of each of said passages 6, and the outlet slits 8 of said tips 7 being arranged substantially parallel with each other and transversely of the projection 5. The projection 5 is also provided 60 in opposite sides thereof between the burner tips 7 with substantially parallel grooves 9 which open through the top of the projection and are separated by a wall 10 terminating short of the upper end of the projection 5, as clearly shown in Figure 2, said grooves being disposed longitudinally of the projection 5 and substantially in the plane bisecting the angle formed by the convergence 65 of the burner outlets.

70 With this construction when the burner is attached to a gas-pipe or the like, the gas turned on and ignited at the tips 7, the flames B from the tips will merge into each other, as clearly shown in Figure 1, due 75 to the converging of the passages 6 and tips 7. The heat from the flames B will cause a circulation of a current of air upwardly through each of the grooves 9 into the space between the flames B, as indicated 80 by the arrows in Figure 2, and this air entering the flames will cause a substantially complete combustion of the gas leaving the tips 7.

85 The currents of air rising through the two grooves 9 will, when they reach the top of the wall 10, impact with each other so as to spread substantially in the plane bisecting said angle of convergence of the burner tips and upwardly into the flames. This complete combustion of the gas makes 90 the flames B substantially white in color, brilliant and of a quality and quantity favorably comparable with the light produced by the well-known incandescent mantles. I have found that by varying the 95

100 depth of the grooves 9 the width of the flames B can be varied, and that different shaped tops on the wall 10 will produce different shapes of flames. Thus, an increase in the depth of the grooves 9 will 105 produce a wider flame, and a square top on the wall 10 will produce substantially a square flame.

110 A plurality of superposed layers of fine mesh wire fabric 11 are preferably arranged in the tubular portion 1 of the burner between the gas-pipe and the chamber 4 so

as to filter the gas and provide a uniform flow thereof through the burner tips.

While I have shown and described one possible embodiment of my invention, it will

5 be understood that this is only for the purpose of illustrating the principles thereof, and that many modifications and changes can be made in the detail construction of the gas burner without departing from the 10 spirit or scope of the invention. Therefore, I do not desire to be understood as limiting myself except as required by the following claims when construed in the light of the prior art.

15 Having thus described the invention, what I claim is:

1. A gas-light burner including a body portion having a pair of spaced converging burner outlets the flames from which merge 20 together, said body portion being provided at opposite sides thereof between said burner outlets with substantially parallel grooves disposed substantially in the plane bisecting the angle formed by the convergence 25 of said outlets and opening through the top of said body portion, where-

by the heat from said flame draws a current of air upwardly through each of said grooves into the space between said burner outlets where said currents impact with each other 30 and spread into said flames.

2. A gas-light burner including a body portion having a pair of spaced converging burner outlets the flames from which merge together, said body portion being provided 35 at opposite sides thereof between said burner outlets with substantially parallel grooves disposed substantially in the plane bisecting the angle formed by the convergence of said outlets and opening through the top 40 of said body portion, said grooves being separated by a wall terminating short of the top of the said body portion, whereby the heat from said flames draws a current of air upwardly through each of said grooves 45 over the top of said wall where said currents of air impact with each other and are caused to spread substantially in said plane bisecting the angle of convergence of the burner outlets and upwardly into said 50 flames.

FRANCIS DE GRUCHY.
